INVENTOR
August Wolff
BY *C. P. Goedel*
ATTORNEY.

UNITED STATES PATENT OFFICE.

AUGUST WOLFF, OF NEW YORK, N. Y.

WINDOW.

Application filed March 21, 1922. Serial No. 545,548.

To all whom it may concern:

Be it known that I, AUGUST WOLFF, a citizen of the United States, and resident of the borough of the Bronx, county of the Bronx, city and State of New York, have invented 5 certain new and useful Improvements in Windows, of which the following is a specification.

This invention relates to improvements in 10 windows and particularly to types used in connection with window frame structures having a curved upper portion and in which the window sash raising space is restricted.

The principal object of the invention is to 15 provide a transparent and flexible window pane and sash which may be raised under conditions where a rigid pane could not be utilized.

Another object is to provide means where- 20 by the window pane and its frame may be guided in a curved pathway as it is raised, both frame and pane being of sufficient flexibility to readily permit of bending in the operation of raising.

25 A still further object is to provide a structure which is sufficiently flexible to permit it to be bent or curved to a relatively small radius without fracture.

These and other objects are attained by 30 the novel construction and combination of parts hereinafter described, and shown in the accompanying drawings, forming a material part of this specification, and in which—

35 Figure 1 is a fragmentary front elevation of a curved window frame showing a sash and pane made in accordance with the invention;

Figure 2 is a vertical sectional view there- 40 of, taken on the line 2—2 of Figure 1;

Figure 3 is an enlarged fragmentary sec- 45 tional view taken on line 3—3 of Figure 1;

Figure 4 is a plan view of the window sash;

Figure 5 is a transverse sectional view 50 taken on line 5—5 of Figure 4; and

Figure 6 is an enlarged fragmentary sec- 55 tional view taken on line 6—6 of Figure 4.

In a window frame having a curved upper portion, it is often desirable to raise the window sash for the purpose of ventilation, and also for unobstructed observation, but in these structures, it is impossible for the sash to be raised vertically to a desirable 60 extent because of insufficient room there-

above and the curvature of the window frame.

In order to permit the raising of the sash in a satisfactory manner, it is necessary that the window pane and its attached sash be 60 sufficiently flexible that it may curve in conformity with the frame structure, which obviously cannot be done with rigid panes such as glass.

In the carrying out of this invention, a 65 flexible pane 10 is used, made of material which does not obscure the vision, is not inflammable, and which is readily adapted to conform with the curvature of the window frame. The sash sides 11 are also made of 70 flexible material and are joined at the top and bottom of the sash by relatively rigid bars 12, the plate or pane 10 being secured to the sash sides 11 and the bars 12 in any preferred manner, as by screws 14 and 15, 75 respectively. Of course, rivets or other suitable forms of securing means may be employed in place of the screws 14 and 15, if desired.

The side elements 11 are suited to engage 80 within slide-ways 18, formed in the window frame curved at their upper portions 19 and formed between rigid outer and inner guides 20 and 21 respectively. These guides are connected at the top by a rigid cross- 85 member 23 and at the bottom by a window sill 24, having a plate 25 on which the sash frame may be seated when in a closed position.

An angular flanged bar 27 is provided 90 with lugs or hand grips 26 and is secured to the bottom member 12 of which bar 27 is a part, a corresponding flanged element 28 being a part of the upper member 12. Outer angle bars 30 having vertical portions 95 31 are secured to the top cross bar 12. A bar 30 is also secured to the lower part of the sash. The screws or rivets 15 pass through the angle bars 27 and 30, cushion elements 32 and plate 10, whereby all the 100 several members are united together.

Extending outwardly and rearwardly of the sash from the screws 14 are studs 35, having semi-spherical ends 36 adapted to operate in suitably shaped recesses 40 105 formed in the outer window guides 20, so that the sash is positively guided as it is raised or lowered.

As will be seen in Figure 3, the groove 40 may be formed in an auxiliary plate 41, so 110

as to accurately guide and maintain the sash in position.

The pane 10 as shown in Fig. 4, is preferably reinforced with pliable wire netting 50, made by weaving longitudinally extending wires and expanding the spaces therebetween in a well known manner.

Although the sides 11 of the sash are flexible, they are so supported by the rigid guides 20 and 21 of the guide ways 18 as to enable force applied to the hand grips 26 to be transmitted to the entire sash in raising and lowering it without distortion of the sash, other than the lateral bending of the sides 11 and the pane 10. The window is further caused to retain its shape by the construction of the upper and lower bars 12, which are in the form of rigid members, and the window is still further held against distortion in the plane of the pane 10 by the engagement of the studs 35 in the recesses 40 of the auxiliary plate 41. From the foregoing, it will be apparent that the window of this invention may be readily raised and lowered in its guide-ways, even though the guide-ways are very sharply curved, and that it will retain its original shape and condition after long-continued use so that its free movement in its guide-ways will not be interfered with.

Having thus described my invention and set forth the construction and manner of its use, what I claim as new, and desire to secure by Letters Patent, is—

1. In a window, the combination of a frame having lateral guide ways comprising inner and outer members curved at their upper portion, one of said guide members being provided with a longitudinal recess, and a sash having a flexible pane, flexible side bars and substantially rigid cross bars, one of said bars having studs connected therewith engaging the recess of said guide

ways, and upper and lower angle iron cross bars connected with the first named cross bars.

2. In a window, the combination of a frame having lateral guide ways comprising inner and outer members curved at their upper portion, one of said guide members being provided with a longitudinal recess, and a sash having a flexible pane, flexible side bars, and substantially rigid cross bars, the side bars having studs connected therewith engaging the recesses of said guide ways, and upper and lower angle iron cross bars connected with the first named cross bars.

3. In a window, the combination of a frame having lateral guide ways comprising inner and outer members curved at their upper portion, one of said guide members being provided with a longitudinal recess, and a sash having a flexible pane, flexible side bars and substantially rigid cross bars, one of said bars having studs connected therewith engaging the recesses of said guide ways, and cushioning members between said cross bars and pane.

4. In a window, the combination of a frame having lateral guide ways comprising inner and outer members curved at their upper portion, one of said guide members being provided with a longitudinal recess, and a sash having a flexible pane, flexible side bars and upper and lower substantially rigid cross bars, the lower cross bar having hand lifts, one of said side bars having studs engaging the recesses of said guide ways, and upper and lower angle iron cross bars connected with the first named cross bars.

In testimony that I claim the foregoing as my invention, I have signed my name hereunder.

AUGUST WOLFF.
